REFRIGERATING DISPLAY CASE

Julius Everett Marsh, Jr., High Point, N. C.

Application March 15, 1935, Serial No. 11,363

8 Claims. (Cl. 20—56.5)

This invention relates to improvements in refrigerating display cases such as are commonly used for the display and storage of meat or any other food products in grocery or similar stores.

More particularly this invention relates to means for preventing condensation or frost from forming on the windows of display cases.

Prior to this invention numerous window constructions have been designed which were intended to accomplish this purpose. These windows usually consist of a plurality of glass panes which are spaced apart and are sealed in window frames to form airtight compartments between the individual glasses. It has also been suggested to replace the moist air in these compartments by artificially dried air through valves in the walls of the compartments and to close the valves by means of screw-threaded plugs.

Various constructions are also known for mounting the individual glass panes in window frames consisting of a variety of materials, such as rubber stripping in combination with wood molding, various putties and cements.

The primary object of the present invention is to provide a structure which is an improvement of the usual manner and means of mounting and sealing a plurality of glass panes with respect to each other and against the outer atmosphere so as to obtain a plurality of airtight compartments. Another object is to remove the air from airtight compartments between glass panes, to replace the same by carbon dioxide gas and to seal the compartments after the replacement. Another object is to provide adjustable means for subjecting the sealing means of such airtight compartments to pressure to insure a perfect and permanent closure. Another object is to obtain a unitary structure of multiglazed windows which is complete in itself and which can be easily manufactured and assembled. This unit can be safely and easily transported and installed in display cases or any other places where such windows are desired.

Another object of the present invention is to prevent the destruction of the mounting and sealing means from shocks, vibration or pounding.

It has been found by long experience that the known means for mounting and sealing the individual glass panes are unsatisfactory in various respects. After continued use for some length of time, air and moisture would seep into and deteriorate the sealing means, and consequently air and moisture would enter the compartments between the glass panes. To overcome or neutralize any seepage of moist air into the compartments,

the prior art provides various means, for instance, continued or repeated circulation of dry air in the compartments, repeated evacuation of the compartments, or the inclusion of materials in the spaces between the glasses which are able to absorb moisture from the atmosphere in these spaces.

The present invention is designed to overcome all these and other disadvantages of the prior art constructions. A compartment once properly sealed will remain that way, the sealing means are not affected by any vibration or pounding and the gaseous filling which does not condense under changes of temperature remains undiluted by moisture and air.

Other objects and advantages of this invention will be apparent from the following disclosure and claims forming a part of this application.

In the drawings:

Fig. 1 is a horizontal section showing parts of the glass enclosed compartments and the various sealing means.

Fig. 2 is an elevation of a portion of the exterior pressure strip.

Fig. 3 is a section on lines 3—3 of Fig. 2.

Fig. 4 is an elevation of a portion of the interior pressure strip.

Fig. 5 is a section on lines 5—5 of Fig. 4, while

Fig. 6 is a horizontal section similar to that of Fig. 1 and showing a modification of my invention.

In the preferred embodiment of my invention illustrated in Figs. 1 to 5, 2 designates the front wall of a display case of the usual construction having outer and inner liners 4 and 6 of insulating material such as fiber board, pressed wood or the like and a liner 8 of galvanized iron or similar material secured to the face of the inner liner 6.

An exterior rectangular frame member 10 made of steel or similar material comprises a channel portion 12 formed by an outer flange 14 and an inner flange 16. Flange 14 is of rectangular cross-section and is bent upon itself so as to form a layer of double thickness. Holes 18 are provided in this flange for the insertion of screws 20. A rectangular extension 22 of this flange 14 is provided with holes 24 for securing the frame 10 to the front wall 2 of the display case by means of screws 26. The inner flange 16 is provided with a protruding portion 28 and holes 30 for the insertion of screws 32.

A liner 34 of heat-insulating material such as wood or the like, preferably ashwood, is placed in the channel portion 12 of frame 10. Screws 20 and 32 are tightened in the liner 34 to secure

the frame 10 thereto. An endless molded rubber stripping 36 containing channels 38 rests against the liner 34 and is surrounded at one side by the protruding portion 28 of the frame 5 10 against which it abuts. Glass panels 40 are inserted in the channels 38 which tightly but resiliently grip the same, forming airtight compartments 42 between adjacent glasses. Two exteriorly threaded valve tubes 44 are located in 10 each compartment, one at the top near one side thereof and the other at the bottom near the opposite side. These valve tubes extend from the interior of the compartments 42 through apertures in the molded rubber stripping 36 and similar 15 apertures in the liner 34 into a recess 46 which may be provided in the liner 34 or in the wall 2 of the display case proper. The valve tubes 44 are suitably tightened to the stripping 36 and the liner 34 by means of resilient washers 48 and nuts 50. Valve caps 52 carrying resilient washers 54 are screwed over the end of the valve shaft for providing an airtight closure for the same after the complete window structure has been assembled.

25 An interior rectangular channel-like frame 56 of steel or similar material of a shape similar to frame 10 is provided with an exterior flange 58 and an interior protruding flange 60. Screws 62 pass through holes 64 in the frame 56 for 30 adjustably securing the frame to the liner 12 and compressing the stripping 36. It is obvious that by this compressing action the stripping is pressed against the individual glass panes 40 insuring an absolutely tight and permanent closure 35 of the compartment 42.

After assembling the complete window unit, carbon dioxide gas is passed through one of the valves 44 of each compartment 42 for removing the atmosphere from the compartment through 40 the corresponding valve in the other side of the compartment. After completely removing the atmosphere and substituting the same by carbon dioxide gas the two valves 44 of each compartment are closed by means of the valve cap 52.

45 The complete window assembly is now ready for its insertion into the display case to which it is secured by means of the screws 26 in the exterior frame 10.

In the modification shown in Fig. 6, a U-shaped 50 liner 34' of steel or similar material is used in place of the liner 34 of insulating material of the preferred form of the invention shown in Fig. 1. An exterior frame member 10' has an outer short flange 14' and an inner protruding flange 16'. A rectangular extension 22' on the outer flange 14' fits into a cut-out portion or groove 23 of the liner 4 and is secured to the wall 2 of the display case by screws 26', while the inner side of the flange 16' bears against the 55 molded rubber stripping 36. Due to the U shape of the liner 34' a space 46' is obtained for the location of the valve 44 and its securing and sealing members 48, 50, 52 and 54.

It will readily be seen that by my new invention any seepage of air or moisture into the compartments or of carbon dioxide gas from the compartments is completely and permanently avoided. It will also be seen that by the invention a unitary window structure is formed 70 which is complete in itself. This complete structure can be built independently of the body of the display case, the display window can be transported separately from the display case, breakage of glass panes can therefore be better avoid-

ed, and the complete unit can be installed without difficulty in the display case at the place where the case is intended to be used. By my new invention it is likewise possible to replace broken display windows of display cases or the like easily at their place in the store without sending the complete case to the manufacturer or repair shop.

The form shown in Figs. 1 to 5 is preferred to the form shown in Fig. 6 because the insulating liner 34 prevents the conduction of heat or cold through the window frame. Otherwise a frosting of the edges of the outer pane of glass might take place.

The molded rubber stripping is used not only for the sealing of the compartments but also to lessen shocks or vibration to which the display case or the window frame might be subjected.

I claim:

1. A self-contained window unit comprising an exterior and an interior metallic frame, said frames having flanges thereon, an endless molded rubber stripping between said frames, said flanges closely surrounding and gripping said stripping, said stripping having endless grooves 25 therein, a plurality of glass plates resting along their edges in said grooves and being snugly surrounded by the walls of said grooves, adjustable means on said interior frame for adjusting the distance between said frames and for compressing 30 said rubber stripping, and means on said exterior frame for securing said complete unit in a window opening.

2. A self-contained window unit comprising an exterior and an interior metallic frame, a plurality of glass plates in spaced relation between said frames, resilient means between said frames, said glass plates resting along their edges in said means and being snugly surrounded thereby, so as to form airtight compartments between 40 adjacent glass plates, means for replacing the atmosphere in said compartments by carbon dioxide gas, said means comprising valves extending through said resilient means and into said compartments, means for sealing said valves, adjustable means on said interior frame for compressing 45 said resilient means, and means on said exterior frame for securing said complete unit in a window opening.

3. A self-contained window unit comprising an exterior and an interior metallic frame, said frames having flanges thereon, an endless molded rubber stripping between said frames, said flanges closely surrounding and gripping said 55 stripping, said stripping having endless grooves therein, a plurality of glass plates resting along their edges in said grooves and being snugly surrounded by the walls of said grooves so as to form airtight compartments between adjacent glass plates, valves extending through said stripping and into said compartments, means for sealing said valves, adjustable means on said interior frame for adjusting the distance between said frame and for compressing 60 said rubber stripping, and means on said exterior frame for securing said complete unit in a window opening.

4. A window comprising an exterior and an interior frame, heat insulating means between 70 said frames, means on said frames for securing said frames to said heat insulating means, a plurality of glass plates in spaced relation between said frames, resilient means between said frames, said glass plates resting along their edges 75

in said resilient means and being snugly surrounded thereby and adjustable means on said interior frame for compressing said resilient means.

5. A self-contained window unit comprising an exterior and an interior metallic frame, heat insulating means between said frames, means on said exterior frame for securing said frame to said heat insulating means, a plurality of glass plates in spaced relation between said frames, resilient means between said frames, said glass plates resting along their edges in said resilient means and being snugly surrounded thereby, means on said interior frame for adjusting said frame with respect to said heat insulating means and for compressing said resilient means.
10. 6. A self-contained window unit comprising an exterior and an interior metallic frame, heat insulating means between said frames, means on said exterior frame for securing said frame to said heat insulating means, a plurality of glass plates in spaced relation between said frames, resilient means between said frames, said glass plates resting along their edges in said resilient means and being snugly surrounded thereby, means on said interior frame for adjusting said frame with respect to said heat insulating means and for compressing said resilient means.
15. 7. A self-contained window unit comprising an exterior and an interior metallic frame, heat insulating means between said frames, means on said exterior frame for securing said frame to said heat insulating means, a plurality of glass plates in spaced relation between said frames, resilient means between said frames, said glass plates resting along their edges in said resilient means and being snugly surrounded thereby, means on said interior frame for adjusting said frame with respect to said heat insulating means and for compressing said resilient means, said interior frame being secured to said heat insulating means, and means on said exterior frame for securing the complete unit in a window opening.

20. 8. A self-contained window unit comprising an exterior and an interior metallic frame, heat insulating means between said frames, means on said exterior frame for securing said frame to said heat insulating means, an endless molded rubber stripping between said frames and resting on said heat insulating means, said flanges closely surrounding and gripping said stripping, said stripping having endless grooves therein, a plurality of glass plates resting along their edges in said grooves and being snugly surrounded by the walls of said grooves so as to form airtight compartments between adjacent glass plates, said heat insulating means having apertures therein, valves secured in said apertures and extending through said stripping and into said compartments, means on said interior frame for adjusting said frame with respect to said heat insulating means and for adjustably compressing said rubber stripping, means on said interior frame for guiding the same with respect to said heat insulating means, said interior frame being secured to said heat insulating means, and means on said exterior frame for securing the complete unit in a window opening.

JULIUS EVERETT MARSH, JR.

resilient means between said frames, said glass plates resting along their edges in said resilient means and being snugly surrounded thereby, means on said interior frame for adjusting said frame with respect to said heat insulating means and for compressing said resilient means, means on said interior frame for guiding the same with respect to said heat insulating means, said interior frame being secured to said heat insulating means, and means on said exterior frame for securing the complete unit in a window opening.

5. A self-contained window unit comprising an exterior and an interior metallic frame, said frames having flanges thereon, heat insulating means between said frames, means on said exterior frame for securing said frame to said heat insulating means, an endless molded rubber stripping between said frames and resting on said heat insulating means, said flanges closely surrounding and gripping said stripping, said stripping having endless grooves therein, a plurality of glass plates resting along their edges in said grooves and being snugly surrounded by the walls of said grooves so as to form airtight compartments between adjacent glass plates, said heat insulating means having apertures therein, valves secured in said apertures and extending through said stripping and into said compartments, means on said interior frame for adjusting said frame with respect to said heat insulating means and for adjustably compressing said rubber stripping, means on said interior frame for guiding the same with respect to said heat insulating means, said interior frame being secured to said heat insulating means, and means on said exterior frame for securing the complete unit in a window opening.
